UNITED STATES PATENT OFFICE.

JAMES H. RAND, JR., OF TONAWANDA, NEW YORK, ASSIGNOR TO RAND KARDEX BUREAU, INC., OF TONAWANDA, NEW YORK, A CORPORATION OF DELAWARE.

CARD INDEX DEVICE.

Application filed April 14, 1923. Serial No. 632,179.

This invention relates to card indexes, and more particularly to that type of index in which a plurality of cards are maintained in overlapping arrangement in a tray or drawer with the edges of the card projecting one beyond the other.

In indexes of this kind card holders have been provided having means for attachment to the supporting tray and having provision for holding a plurality of cards. For example, one type of holder such as is illustrated in the drawings of this application, has suitable tongues for engaging the usual side flanges of the tray or drawer, and pockets or other means for supporting a pair of cards, one on the upper face of the holder and another on the lower or rear side of the holder. The cards so associated in pairs may bear a desired relation one to the other, in other words the cards on the upper or front face of the holders may be of a certain type or contain a certain class of information, and those on the lower or rear sides of the holders may be of different type or contain a different class of information, which it is desired to associate with the cards or the information on the upper sides of the holders. In index installations of this character it is desirable that the presence or absence of cards on the rear sides of the holders may be noted without moving the upper cards or the holders and it is also desirable that the rear cards on the holders may be identified without moving the upper cards or the holders.

The objects of the present invention are to provide improvements in index devices of the type referred to, whereby the presence or absence of cards on the rear side of the holders may be noted without moving any of the holders or cards thereon; also to provide an improvement in indexes whereby the cards on the rear as well as the front sides of the holders may be readily identified without moving any of the cards or holders; and also to provide improvements in card index devices in the other respects herein-after set forth and claimed.

In the accompanying drawings:

Fig. 1 is a plan view of a portion of an index embodying the present invention.

Fig. 2 is a plan view of a portion thereof with the upper cards of the holders removed.

Fig. 3 is a sectional elevation of a card holder with a pair of cards connected

thereto, removed from the supporting device, and embodying the present invention, on line 3—3, Fig. 1, but on an enlarged scale.

Fig. 4 is a fragmentary sectional perspective view of the holder and cards.

Fig. 5 is a plan view of a card holder and card as in Fig. 1, the upper card being broken away to disclose the underlying parts of the holder.

Fig. 6 is a plan view of the members illustrated in Fig. 5 with the upper card in an offset position.

Fig. 7 is a plan view of a holder showing in full and broken lines a modified form of upper card in two positions.

Fig. 8 is a plan view of a holder, with still another form of upper card.

Fig. 9 is a fragmentary view thereof with the card in an offset position.

Referring to Figs. 1 to 6 inclusive, A designates a portion of a supporting tray or drawer having the usual side flanges B. 10 designates a plurality of card holders of sheet material provided with tongues 11 which are adapted to take under the flanges B of the tray and whereby the holders are detachably secured to the tray in overlapping relation. These holders may have hinged card-supporting portions 12, as illustrated, and may be provided adjacent their free ends with card-receiving pockets 13 of transparent material, secured in position on the holder by staples 13a. The holders may be provided, as shown, with slits 14 or other means for engaging the upper corners of the cards to assist in retaining the cards on the holders. Other forms of tray or of card holders and attaching means therefor may be used if desired.

According to the present invention, the cards are associated on both sides or faces of the several holders. For example, a pair of cards is shown in the drawings, the cards of the pair being disposed on opposite sides of the holder in substantially coincident superposition. The present invention includes means whereby, while being associated in pairs such as described, the presence or absence of one of the cards of a pair may be noted by the user of the index without moving any of the cards or any of the holders, and also means whereby either of the cards of a pair may be identified by the user of the index without moving any of the cards.

2
or any of the holders. Preferably the upper card of each pair is so formed as to expose a portion of the lower card of each pair to the view of the user of the index. In the 5 form of the invention illustrated, this is accomplished by providing an aperture or cut-out portion in the upper card of a pair, whereby a portion of the lower card may be viewed through the aperture or cut-out portion of the upper card. For purposes of 10 illustration, a pair of cards only is shown on each holder, but it is obvious that a greater number of pairs of cards may be used side by side on each holder, if desired. Thus for 15 example, in Figs. 1 to 6, 15 designates a card supported on the front or upper face of the card holder and 16 designates a card supported on the rear or lower face of the card holder. The upper card 15 is provided with 20 an aperture or recess 17, which permits a view of a portion of the lower card. Thus it is apparent from Fig. 1 that when the cards are in normal positions in the holder the presence or absence of any of the lower 25 cards on the holders may be noted without moving the upper cards or without moving the holders. The view of a portion of the lower card is permitted through the card holder by any suitable means. With the type 30 of holder illustrated, a portion of the holder is cut out as indicated at 18, but it is understood that the same results may be obtained by other means, if desired.

In the form illustrated in Figs. 1 to 6, the 35 lower cards are provided at their portions which are displayed through the apertures or recesses with suitable symbols or the like 19, thereby providing positive signals to indicate the presence of cards on the rear or 40 under side of the holders. While illustrated in these figures, it is not essential that a positive distinctive signal symbol be utilized, as the same results may be accomplished by providing a lower card of distinctive color or appearance from the upper card, whereby its 45 presence may be readily noted through the aperture or recess in the upper card.

In Fig. 7, there is shown an upper card 15^a and the presence of the lower card 16^a is emphasized and an additional purpose served by providing the lower card with an index designation 19, the name of a person being illustrated on the card shown, which designation is viewed through the cut-out portion 17^a in 50 the upper card and a corresponding cut-out portion in the holder, and not only indicates the presence of a card on the lower side of the holder, when the card is in place, but also gives the designation of the person or thing 55 to which the data on the card refer.

As illustrated in Figs. 6 and 9 and in broken lines in Fig. 7 of the drawings, this 60 invention renders it possible to use the upper cards on the holders of the index as signals to mark a place in the index or call the at-

tention of the operator to any particular card or holder, the cut-out portion of the upper card permitting that card to be moved over in the sheath at the bottom of the holder, to a position where the card is offset from the 70 side of the holder, the stapled end of the sheath or pocket taking into the cut-out portion of the card. In such position the lower edge of the non-projecting portion of the card rests in the pocket and holds the card 75 in position on the holder.

Figs. 8 and 9 illustrate still another form of upper card, shown and designated as 15^b. This upper card has a cut-away portion 17^b extending to one of its side edges, the holder 80 being provided with an aperture 18^b, a portion of the lower card 16^b being displayed through said aperture.

I claim as my invention:

1. In an index device, the combination 85 of a card holder having means for attachment to a support, and parts for releasably holding a card on one side thereof, said holder having an opening therein whereby a portion of said card at one side of said holder 90 may be viewed from the opposite side of the holder without moving said holder.

2. In an index, the combination of a plurality of index cards, a card holder having a card-supporting portion with an aperture 95 therein and adapted to support cards on opposite sides thereof, one of said cards having a cut-out portion adapted to register with the aperture in said holder, whereby a portion of the card on the opposite side of said 100 holder may be viewed through said aperture.

3. In an index device, the combination of a plurality of separate index cards, and means for releasably attaching said cards to a support, said cards being arranged in 105 pairs, the cards of each pair being in substantially coincident superposition, the upper card of each pair having an opening in a portion thereof, whereby the presence of the card therebeneath may be noted without 110 lifting the upper card or moving said attaching means.

4. In a card index, the combination of a plurality of index cards arranged in pairs, the cards in each pair being in substantially 115 coincident superposition, the several pairs of cards being arranged in overlapping relation, and means for detachably connecting the cards to a support, the upper card of each pair being formed so as to present a 120 portion of the lower card to view when the cards are mounted on said support.

5. In an index device, the combination of a plurality of cards, a card holder having a 125 pocket at one edge adapted to receive portions of said cards for supporting the cards on the holder, one of said cards having a cut-out portion whereby a portion of an underlying card may be viewed therethrough, said cut-out portion permitting the card to 130

be shifted laterally on said holder, so that a portion of it projects from the edge of the pocket.

6. In an index device, the combination of 5 a card holder comprising an attaching portion adapted to engage a support, and a card-holding portion hinged to said attaching portion, parts at the top and bottom of

said card-holding portion for engaging cards to retain them thereon, and cards 10 mounted on the front and rear sides of said holders and having portions engaging said card-retaining parts on said holder, said front cards having apertures through which portions of said rear cards may be viewed.

JAMES H. RAND, JR.
